B. STEWART,
PNEUMATIC ARCH AND HEEL SUPPORT,
APPLICATION FILED OCT. 16, 1918.

Patented Aug. 26, 1919.

Inventor

Benjamin Stewart

By J. C. H. M. Surgeon

Atty's.

UNITED STATES PATENT OFFICE.

BENJAMIN STEWART, OF ERIE, PENNSYLVANIA.

PNEUMATIC ARCH AND HEEL SUPPORT.

1,313,924.

Specification of Letters Patent. Patented Aug. 26, 1919.

Application filed October 16, 1918. Serial No. 258,385.

To all whom it may concern:

Be it known that I, BENJAMIN STEWART, a citizen of the United States, residing at Erie, in the county of Erie and State of Pennsylvania, have invented certain new and useful Improvements in Pneumatic Arch and Heel Supports; and I do hereby declare the following to be a full, clear, and exact description of the invention, such as 5 will enable others skilled in the art to which it appertains to make and use the same, reference being had to the accompanying drawings, and to the letters of reference marked thereon, forming part of this specification.

15 My invention relates to pneumatic arch and heel supports, to be utilized in shoes, to support fallen arches, and the heels of the wearers by an elastic support that may be varied as the necessities of the wearer require.

20 The device consists substantially of an inclosed receptacle adapted to be inserted in a shoe under the arch and heel of the wearer adapted to retain air therein so as to operate 25 as an elastic cushion, and valve mechanism extending downward therefrom, whereby a greater or less amount of air may be pumped therein.

25 The features of my invention are herein- 30 after fully set forth and described, and illustrated in the accompanying drawings in which:

35 Figure 1, is a side view in elevation of a portion of a shoe having parts thereof broken away, illustrating one form of my invention.

40 Fig. 2, is a side view in elevation of a portion of a shoe having parts thereof broken away, illustrating a modification of the valve mechanism of my invention.

45 In these drawings A is the body of a shoe, B the heel, and C the sole, all of the usual construction.

50 In the shoe and resting upon the inside of the sole thereof I place an inclosed receptacle D preferably of rubber or other suitable air proof flexible and yielding material, preferably more or less elastic, and extending from the back end of the heel portion A'

of the shoe, to and some distance over the 50 ball portion C' of the sole C of the shoe, this receptacle being made of such width and shape as to conform to the size and width of the inside of the sole of the shoe. Secured in the lower wall d of this receptacle 55 is a stem E, having a suitable check valve e therein. This check valve e, the stem E of which extends downwardly through a hole c in the sole C of the shoe adjacent to the front end b of the heel B, is 60 secured in place by means of a screw collar E', on the valve stem E, screwed up against the lower surface of the sole C.

65 The lower end of the valve stem E is provided with a screw thread e', in the usual manner to receive an air-pump for filling the receptacle D with air, and to receive a cap E² when the air-pump is removed to prevent dirt from interfering with the valve mechanism.

70 In Fig. 2, I show a modification of the valve mechanism of my device, in which the stem E is provided with an extension E³, which extends backward through a hole 75 c' in the heel B to the rear thereof where it is provided with a removable cap e², to exclude dirt, as hereinbefore described.

75 I have not shown an insole of leather or other suitable material, resting on the top of the receptacle D and extending forward to the toe of the shoe, as it is obvious that my device can be utilized equally well either or without such insole, as suits the convenience of the wearer.

80 In operation the receptacle D is filled with air at suitable pressure to expand the same so as to form a suitable elastic support for the fallen arch and heel of the wearer of the shoe; such pressure being varied according to the amount of air pumped into the 90 receptacle D.

85 Having described my invention so as to enable others to construct and utilize the same, what I claim as new and desire to secure by Letters Patent is:

90 A pneumatic arch and heel support consisting substantially of an air-tight flexible chamber extending from the heel to the ball

of the foot, and adapted to fit and conform to the inside of the shoe, a threaded valve-stem secured in the lower wall of said chamber and extending down through the shoe-sole adjacent to the front of the heel, a screw threaded collar on said valve-stem engaging the lower surface of the shoe-sole

whereby said chamber is clamped to the shoe and thereby secured from movement, and a valve in said valve-stem whereby the inflation of said chamber may be varied, substantially as set forth.

In testimony whereof I affix my signature.
BENJAMIN STEWART.
